UNITED STATES PATENT OFFICE.

WINFIELD SCOTT SMITH, OF WHARTON, OHIO.

CLEVIS.

No. 923,806.

Specification of Letters Patent.

Patented June 1, 1909.

Application filed March 27, 1909. Serial No. 486,199.

To all whom it may concern:

Be it known that I, WINFIELD SCOTT SMITH, a citizen of the United States, residing at Wharton, in the county of Wyandot 5 and State of Ohio, have invented certain new and useful Improvements in Clevises; and I do hereby declare the following to be a full, clear, and exact description of the invention, such as will enable others skilled in the art to 10 which it appertains to make and use the same, reference being had to the accompanying drawings, and to the letters of reference marked thereon, which form a part of this specification.

This invention relates to new and useful 15 improvements in clevises, and comprises various details of construction and combinations and arrangements of parts which will be hereinafter fully described and then specifically defined in the appended claim.

My invention is illustrated in the accompanying drawings, in which:—

Figure 1 is a perspective view of a clevis made in accordance with my invention. 20 Fig. 2 is a detail perspective view showing the parts separated, and Fig. 3 is a sectional view.

Reference now being had to the details of the drawings by letter, A and A' designate 25 two sections of which the clevis is constructed each of which has a lug B projecting therefrom and adapted to engage an aperture C in a whiffletree or evener, and one of said sections A has a curved end D which is longitudinally slotted, as at D', while the other section A' is provided with a contracted 30 curved end E, and F designates a pivot pin passing through registering apertures in the two sections in the manner shown, and affording means whereby the two sections are 35 pivoted together. The section A' has an

eye H upon the concaved edge of the curved end thereof, said eye being adapted to project through the slot in the manner shown clearly in the drawings, and K is a key 45 adapted to be passed through said eye in the manner shown in order to hold the parts in locked relation one with the other. It will be noted that the curved end of the section A is beveled slightly and is adapted to contact 50 with the flattened and widened surface upon the inner edge of the section A'. When the two sections are locked together in the manner described, the ends of the two lugs preferably contact with each other, and the opposite edges of the two sections which are 55 hinged together are flush with each other.

When it is desired to apply the clevis or detach it from any object, the key is removed, which will allow the two free ends 60 of the clevis to swing apart. When the key is replaced, the parts will be securely held in locked relation one with the other.

What I claim to be new is:—

A clevis made up of two sections having 65 curved ends, one of which is slotted, a pivot pin passing through registering apertures in the walls of said slotted section and upon which the curved end of the other section is pivotally mounted, an eye upon one section 70 extending through said slot, a key adapted to pass through said eye and bearing against the inner edges of the curved slotted part of said section, and lugs, one upon each of said sections and in alinement with each other, 75 as set forth.

In testimony whereof I hereunto affix my signature in the presence of two witnesses.

WINFIELD SCOTT SMITH.
